UNITED STATES PATENT OFFICE

DOMENIC A. VALVANO, OF LINDEN, NEW JERSEY

DESIGN FOR A TOY GOLF COURSE

Application filed January 15, 1931. Serial No. 38,317. Term of patent 7 years.

To all whom it may concern:

Be it known that I, DOMENIC A. VALVANO, a citizen of the United States, and a resident of Linden, in the county of Union and State of New Jersey, have invented the new, original, and ornamental Design for a Toy Golf Course, of which the following is a specification.

Reference is had to the accompanying drawings, forming part thereof, wherein—

Figure 1 is a plan view of a toy golf course showing my new design.

Figure 2 is an enlarged fragmentary sectional view on line 2—2 of one of the units shown in Figure 1.

Figure 3 is an edge view of the toy golf course shown in Figure 1.

I claim—

The ornamental design for a toy golf course substantially as shown.

DOMENIC A. VALVANO.
